UNITED STATES PATENT OFFICE

BENJAMIN H. NEWCOMER, OF CHARLESTON, WEST VIRGINIA

RACK

Application filed June 8, 1929. Serial No. 369,391.

The present invention is particularly designed for holding paper bags and the prime object of the present invention resides in the provision of means for holding various sized paper bags so that the same may be conveniently and quickly removed without rumpling or otherwise mussing up the bags.

Another very important object of the invention resides in the provision of a rack structure of this nature which is provided on its rear side with an advertising board.

A still further very important object of the invention resides in the provision of a rack of this nature which is simple in its construction, strong and durable, inexpensive to manufacture, compact and convenient in its arrangement of parts, thoroughly efficient and reliable in use and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a side elevation of the rack embodying the features of my invention,

Figure 2 is a front elevation thereof,

Figure 3 is a rear elevation thereof,

Figure 4 is a top plan view thereof, and

Figure 5 is a sectional view taken substantially on the line 5—5 of Figure 1.

Referring to the drawing in detail it will be seen that numeral 5 denotes a base plate adapted to rest flat on the floor and having in its front corners a pair of bars 6 rising perpendicularly therefrom and in its rear corners, a pair of bars 7 rising therefrom and inclining upwardly and forwardly toward the bars 6. As seen most clearly in Figures 3, 4 and 5 of the drawings, the opposed sides 45 of the front pair of bars 6 and the rear pair of bars 7 converge toward their upper ends. A top plate 8 is mounted on the upper ends of the bars 6 and 7 and has a spindle 9 rising therefrom on which cord or twine in ball 50 or spool form may be mounted.

A signboard such as a blackboard 10 is fitted to the bar 6 to extend thereacross and is in the front so as to be readily seen by the customers in the store and of course advertising indicia may be written thereon. 55

A plurality of superposed shelves 11 are mounted in spaced parallelism between the bars 6 and 7 inclining downwardly and rearwardly and have their lower edges formed with central notches 12 and having thereon 60 clips 14 one to each side of each notch 12. Due to the inclination of the inner faces of the pairs of bars 6 and 7, the width of the shelves 11 is progressively reduced from the lowermost to the uppermost thereof. Rods 65 15 extend across the upper surfaces of the shelves 11 and are spring pressed downwardly by springs 16 anchored on the shelves below or on the bottom 5 as with the lowermost shelf. 70

Obviously different sized bags are placed on the shelves since these shelves decrease in length from bottom to top and the bags are placed under the spring pressed rods 15 and the ends of the bags abut the clips 14. Obviously one bag at a time may be easily removed from the shelves and the groceryman or the like may see at a glance the proper sized bags and conveniently and easily collect the same. 75 From the above detailed description, it will 80 be seen that I have devised an apparatus which is exceedingly simple in its construction, and may be manufactured at a low cost.

The structure further affords convenience in collecting the paper bags and affords an advertising medium for the storekeeper. 85

The present embodiment of the invention has been disclosed in considerable detail merely for the purposes of exemplification since in actual practice it attains the features of advantage enumerated as desirable in the statement of the invention and the above description. 90

It will be apparent that changes in the details of construction, and in the combination and arrangement of parts may be resorted to without departing from the spirit or scope of the invention as hereinafter claimed or sacrificing any of its advantages. 95 100

Having thus described my invention, what I claim as new is:

A rack structure of the class described comprising a base, a pair of front bars rising perpendicularly from the base, a pair of rear bars rising from the base, the opposed sides of the pairs of bars converging upwardly, a plurality of superposed shelves mounted between the bars the widths of which are progressively reduced from the lowermost to the uppermost thereof, spring pressed rods across the shelves and extending beyond the marginal edges thereof and retractile springs secured, at one end, to the opposite end portions of the rods and having their opposite end anchored to the subjacent shelf.

In testimony whereof I affix my signature.
BENJAMIN H. NEWCOMER.
